UNITED STATES PATENT OFFICE.

ROBERT DIXON, OF ARMELLS, MONTANA.

PORTABLE LIGHTING DEVICE.

1,316,431.

Specification of Letters Patent. Patented Sept. 16, 1919.

Application filed April 29, 1918. Serial No. 231,478.

To all whom it may concern:

Be it known that I, ROBERT DIXON, a citizen of the United States, residing at Ar-
5 mells, in the county of Fergus and State
of Montana, have invented new and useful
Improvements in Portable Lighting De-
vices, of which the following is a specifica-
tion.

This invention relates to portable light-
10 ing devices.

An object of the invention is to produce
a device of this character wherein a lamp
and battery may be arranged in a suitable
casing so that the same may be easily car-
15 ried from place to place, the wires between
the lamp and battery being wound on a
spring roller and readily unwound there-
from by a direct pull against the roller,
so that the lamp may be used at any desired
20 distance from the battery and casing, as
is desirable in automobiles and similar ve-
hicles for locating trouble.

It is a further object of the invention to
produce a device of this character in which
25 the roller is of insulating material, the
cores thereof being of electric conducting
material, and the bearings for the cores be-
ing likewise of electric conducting material
so that the wires from the battery may be
30 directly connected to either the bearings or
the projecting ends of the cores which pro-
vide trunnions that are journaled in the
bearings, while the wires from a lamp are
removably secured to the cores, spring
35 means being provided for winding the
roller in one direction, and clutch means
being provided for controlling the spring
means.

With the above and other objects in view
40 the improvement resides in the construction,
combination and arrangement of parts set
forth in the following specification and
falling within the scope of the appended
claim.

45 In the drawings:

Figure 1 is a perspective view of the im-
provement,

Fig. 2 is a similar view with the door of
the casing open and the lamp partly with-
50 drawn therefrom,

Fig. 3 is a horizontal sectional view ap-
proximately on the line 3-3 of Fig. 1,

Fig. 4 is a transverse sectional view ap-
proximately on the line 4-4 of Fig. 3,

55 Fig. 5 is a greatly enlarged sectional view
on the line 5-5 of Fig. 4,

Fig. 6 is a perspective view of the roller,
and

Fig. 7 is a similar view of the bearings.
The casing 10, in the construction illus- 60
trated by the drawings, is of a substan-
tially rectangular formation, but it is to
be understood that the same may be of any
desired shape and size, the casing, however,
being constructed of some suitable non- 65
electric conducting material. The open face
of the casing is normally closed by a hinged
door 11, suitable latching means 12 being
provided for locking the door on the casing.

In the casing, on the ends thereof, are se- 70
cured oppositely disposed bearing members
13 which are of metal or of any other de-
sired electric conducting material. In the
bearings are journaled the trunnions 14 of
the roller 15. The trunnions are of metal 75
or of other suitable electric conducting ma-
terial and are formed with and provide the
ends of cores 16 and 17 which are centrally
embedded in the roller for a considerable
distance but which terminate a suitable dis- 80
tance away from each other. The cores 16
and 17 are engaged by angular elements 18
which are threaded and which, of course,
are arranged in suitable openings in the
roller. The elements 18, however, do not 85
extend to the periphery of the roller, the
outer ends of the same being received in
pockets 19 formed in the roller. By refer-
ence to the drawings it will be noted that
the threaded members 18 of the cores 16 90
and 17 extend in opposite directions with
respect to each other, and consequently the
pockets 19 are arranged on the opposite
sides of the roller 15. On each of the ele-
ments 18 is arranged a washer 20, and on 95
each of the elements 18 is screwed a nut
21. Between the washer 20 and the nut 21
of the respective elements 18 is arranged
the wires 22 connected with the lamp 23,
and it will be apparent that when the roller 100
is turned in its bearings the wires 22 will
be wound therearound. It is also to be un-
derstood that the wires 22 are provided with
a suitable coating of insulating material.

In the casing 10 is arranged a battery 24, 105
the wires 25 and 26 therefrom being di-
rected to the respective bearings 13 and be-
ing attached thereto, preferably by binding
elements 27, and these binding elements may,
if desired, be in the nature of one of the 110
screws employed for securing the bearings to
the ends of the casing. The means for sup-

porting the battery, illustrated by the drawings, comprises spring clips 30 that are bent upon themselves to provide rounded portions 31 that engage the battery. One 5 of the ends of each of the clips is straight and this straight end, indicated by the numeral 32 is secured to one of the walls of the casing 10.

The roller is influenced in one direction 10 by a spring 28 and has one of its ends provided with the usual clutch elements 29 for controlling the spring, whereby when the roller is partly unwound, the same may be held against further turning except when 15 a direct pull is exerted thereon.

From the above it is believed that the simplicity and advantages of the construction will be apparent, it being noted that the device is of a compact nature and it may be 20 readily conveyed from place to place and carried in the pocket of the user. It will be also apparent that the wires 22 may be of any desired length, so that the lamp 23 may be used a considerable distance away 25 from the casing. It is to be understood, and as illustrated by the drawings, that the lamp is controlled by a suitable switch which is indicated by the numeral 30.

What I claim is:

In a portable lighting device, a substantially rectangular casing having an open top, a hinged door therefor and latching means for securing the door closed on the casing, bearings of electric conducting material on the ends of the casing, a spring influenced roller having trunnions received in the bearings, said trunnions being in the nature of electric conductors and extending centrally in the roller from the opposite ends thereof and terminating an approximately equal distance away from the center of the said roller, oppositely extending angularly disposed binding posts on each of the trunnions adjacent to the inner ends thereof, said binding posts having 45 their outer ends received in pockets in the roller, an electric conducting wire connected with each of the binding posts and a lamp connected with said wires, spring clips secured to one of the sides in the casing, a 50 battery supported by said clips, and electric conductors between the poles of the battery and the electric conducting bearings for the rollers.

In testimony whereof I affix my signature.
ROBERT DIXON.
